UNITED STATES PATENT OFFICE

LOUIS D. PEIK, OF MISHAWAKA, INDIANA, ASSIGNOR TO THE AMERICAN FOUNDRY EQUIPMENT COMPANY, OF NEW YORK, N. Y., A CORPORATION OF DELAWARE

TUMBLING MILL

Application filed August 30, 1929. Serial No. 389,385.

The invention relates to tumbling mills for smoothing rough castings and the like.

According to one form which the invention may take the mill comprises a stationary casing in which is positioned a traveling conveyor or belt so arranged as to provide a receptacle for the articles treated. In effect a tumbling barrel is formed having a stationary segment provided by the casing and a movable segment provided by the conveyor. Circular plates may be rotatably mounted on the casing to act as heads for the barrel. The barrel heads may have hollow trunnions and air may be drawn in through one of the heads and air, abrasive and dust may be removed from the other head. Suitable devices may be provided for separating the dust from the spent abrasive. The casing may support suitable blast nozzles for directing abrasive upon the articles to be treated and suitable means may be provided for conveying the spent abrasive which has been removed from the mill to the blast nozzles so that it can be used over and over again. The arrangement may be such that the conveyor moves in one direction to tumble the articles, and when, reversed, it moves to quickly eject the articles from the machine through the charge opening.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a vertical section through a tumbling mill; and

Fig. 2 is a section on the line 2—2 of Fig. 1.

In the following description and in the claims parts will be identified by specific names for convenience, but they are intend-

ed to be as generic in their application to similar parts as the art will permit.

Like reference characters denote like parts in the several figures of the drawings.

Referring to the drawings, the tumbling mill comprises a stationary casing 4 enclosing a movable segment 5. This casing 4 is made up of a pair of end walls 6 and 7 to which the several side wall plates 8 are secured. The end walls 6 and 7 are preferably castings 55 suitably ribbed for strength and having suitable attaching brackets and flanges cast integral therewith, to which a plurality of transverse channels 9 are provided connecting the end walls 6 and 7. The several side 60 wall plates 8 are secured to the end walls 6 and 7 and to these channels 9. These plate members include an upper sheet 10 in the form of an angle having a depending wall and an exhaust sheet 11 having a plurality 65 of suction pipes 12 connected thereto.

The casing end walls 6 and 7 are provided with hollow bosses 34 and 35 in which are journaled hollow projecting posts or shafts 36 and 37 secured to circular barrel heads 75 38 and 39. Each head 38 or 39 comprises a circular plate 100 to which is secured a drum 101 and a removable liner 41 having elongated openings 102. The head 39 is hollow and may be called the intake head since air 80 passes into the barrel as indicated by the arrows. The head 38 is provided with spiral vanes 103 located between the plate 100 and the liner 41. The head 38 may be called the exhaust head because the air, abrasive and 85 dust pass out through this head assisted by the vanes 103. Each drum 101 has a flange 40 on its periphery thereby forming with the projecting liner plate 41 a circular groove 42 90 for a purpose hereinafter described.

Cooperating with the casing 4 and with the barrel heads 38 and 39 and forming the movable segment is the endless conveyor 5 suitably supported upon three pairs of sprockets 95 43, 44 and 45, these sprockets being supported on suitable shafts, two sprockets on each shaft. Secured to the casing end walls 6 and 7, one on each side, are track members 46 and 47 for supporting the endless chain at the 100

point where the articles to be treated exert their weight.

The movable segment or traveling conveyor 5 is made up of chains 52, 53, one on each side, running on the sprockets 43, 44, 45 on each side. These chains are made up of a series of links 54 connected by pins 55 having rollers 56 thereon. Each link 54 has a lateral extension 57 on which seats a pair of angle irons 58 extending the width of the conveyor from one chain to the other. Each extension 57 has a diagonal sealing flange 59 riding in a groove 42 to prevent escape of the abrasive from the tumbling chamber. The angle irons 58 are disposed close together as indicated in Fig. 1 so that no abrasive can pass through the conveyor. For driving the conveyor a spur gear 85 is mounted upon the shaft 84 which supports the lower sprockets 44. Drive gear 85 may be driven by a suitable reversible motor (not shown).

It will be noted that the chains 52, 53 are outside of the blasting chamber and are therefore protected from the direct force of the blasting, while only exposed to the blasting are the angle irons 58 and the liners 41 on the barrel heads, all of which may be replaced when worn. The chain rollers 56 ride on tracks 46, 47 thereby insuring proper support for the weight of the articles being treated, which may be considerable.

The casing is provided with a composite door 13 comprising an upper section 16 and a lower section 17, this door closing the charge opening. The sections are suitably pivoted together by hinges 18 and the upper section is suitably pivoted to the casing by a hinge 21. The lower door section 17 carries suitable nozzle holders 29 for supporting nozzles (not shown) which direct abrasive such as sand on the articles to be treated.

For removing abrasive and dust from the mill a fitting 105 is provided comprising a branch 106 and a branch 108. The branch 106 is illustrated as seating in a groove 107 in hub 36 to provide a sealing arrangement at this point. An exhaust fan or other suction device (not shown) may be attached to the branch 108.

The lower part of fitting 105 provides in effect a receptacle for the abrasive, and has a gate 109 attached thereto by a spring hinge 110 normally holding the gate closed. When a predetermined amount of abrasive has gathered in the fitting the tension of the spring hinge 110 is overcome and the gate 109 opens, allowing the abrasive to fall upon inclined screen 112 and thence into pressure tank 113.

It will be noted from Fig. 1 that the conveyor sags at its lower part between sprockets 43 and 44, and that it is taut at other places. Thus the conveyor is self-tightening, the part fitting against the barrel heads 38 and 39, being kept tight against these heads by the weight of the parts of the conveyor be-

tween sprockets 43 and 44 on the one hand, and between sprockets 44 and 45 on the other hand. It will be noted that the slack occurs mostly between sprockets 43 and 44 where it can do no harm. The pressure of the conveyor against the barrel heads 38 and 39 causes these heads to rotate as the conveyor moves.

To use the apparatus the door 13 is opened and the articles to be treated are placed in the pocket formed by the movable conveyor 5. The door is then closed to the position shown in Fig. 1 and the driving motor started to rotate the gear 85 in such direction as to cause the conveyor to move in the direction indicated by the arrow X in Fig. 1, carrying the articles upwardly. It will be seen that as these articles are carried upwardly they will slide and tumble down continuously as the conveyor moves, exposing all sides thereof to the action of the sand blast coming from the nozzles (not shown) in the nozzle holders 29. The particles removed from the surface of the articles and the spent abrasive collects upon the conveyor and the draft of air through the tumbling chamber and movement of the conveyor causes the abrasive to drift against the head 38. The friction of the conveyor against the head 38 causes rotation thereof and the abrasive passing through the openings 102 is carried by the vanes 103 and delivered out through the hollow shaft 36 together with dust into the fitting 105. The dust is carried out through branch 108 while the abrasive falls into the bottom of the fitting. The abrasive is delivered to the screen 112 by the action above described and this screen discards all coarse particles removed from the articles treated, allowing the abrasive to pass into pressure tank 113 where it is picked up and directed to the nozzle holders 29. The abrasive thereby travels in a closed path and is used over and over again. The air passes into the mill principally through the opening in shaft 37 and through the vents 12 in the top of the casing.

After the articles have been treated sufficiently, if desired the abrasive nozzles are shut off first and the conveyor allowed to run to remove all loose abrasive from the mill. The suction draft is then shut off and the door 13 opened and the driving motor which drives gear 85 is reversed. This reverses the motion of the conveyor 5 and quickly carries the articles out through charge opening onto the floor or receptacle waiting for them.

Thus it will be seen that the above described tumbling mill is rugged in construction, simple and efficient in operation and occupies but small space. The particular construction of movable conveyor provides a most useful arrangement in which the worn parts may be easily replaced. The working parts are removed, as far as possible, from the direct action of the abrasive of the articles.

treated. The utilization of a rotating head to convey the abrasive from the machine assists in making a compact construction. Furthermore the vents 12 provide for additional and necessary air flow into the machine increasing that which is drawn in through the hollow shaft 37 to reduce the resistance to the removal of material through trunnion 36.

This application is a continuation in part 10 of application, Serial No. 298,194, filed August 8, 1928.

While certain novel features of the invention have been shown and described and are pointed out in the annexed claims, it will be 15 understood that various omissions, substitutions and changes in the forms and details of the device illustrated and in its operation may be made by those skilled in the art without departing from the spirit of the invention.

What is claimed is:

1. A tumbling mill for cleaning castings and the like comprising a stationary casing, a head in said casing, a conveyor in said casing for tumbling the articles, said head, part of said conveyor and part of said casing forming a tumbling chamber, and means for removing material from said chamber by said head.

2. In tumbling apparatus for cleaning castings and the like, a stationary casing, a circular, a hollow head in said casing, a hollow trunnion secured to said head and journalled in said casing, a perforated liner plate secured to said head, vanes within said head, a movable conveyor adjacent said head for tumbling the articles, and means for rotating said head to remove material from said casing, part of said conveyor, part of said casing and said head forming a tumbling chamber.

3. In tumbling apparatus for cleaning castings and the like, a stationary casing, circular heads in said casing, the first of said heads comprising a plate, a hollow trunnion secured to said plate and journalled in said casing, a cylindrical wall secured to said plate, a perforated liner plate secured to said cylindrical wall, vanes within said cylindrical wall and extending from said wall to the hollow trunnion, a movable conveyor extending between said heads for tumbling the articles, a suction device connected to said first hollow trunnion and blast nozzles in said casing, and means for rotating said head by movement of said conveyor, said heads, and complementary parts of said casing and conveyor forming a tumbling chamber.

4. In tumbling apparatus for cleaning castings and the like, a stationary casing, circular heads in said casing, the first of said heads comprising a plate, a hollow trunnion secured to said plate and journalled in said casing, a cylindrical wall secured to said plate, a perforated liner plate secured to said cylindrical wall, vanes within said cylindrical

wall and extending from said wall to the hollow trunnion, a movable conveyor extending between said heads for tumbling the articles, a suction device connected to said casing, blast nozzles in said casing, said vanes delivering material from said casing out through the hollow trunnion, said heads, and complementary parts of said casing and conveyor forming a tumbling chamber.

5. In a tumbling apparatus for cleaning castings and the like, a tumbling chamber, means for subjecting the articles being treated in said chamber to a blast of abrasive, a trap having a dump bottom, means for applying suction to the top of said trap, means connecting said tumbling chamber to said trap and for delivering spent abrasive and dust thereto, and means for causing said bottom to dump when a predetermined amount of abrasive is deposited.

6. In tumbling apparatus for cleaning castings and the like, a stationary casing having vents at the top thereof, a movable conveyor for tumbling the articles in said casing, and suction devices for removing matter from the inside of said casing, said vents operating to reduce the resistance of removing the matter from the inside of the casing.

7. In tumbling apparatus for cleaning castings and the like, a stationary casing, a movable conveyor therein, first and second heads with central openings, means journaling said heads in said casing, said casing entirely enclosing said conveyor, said casing, said heads and complementary parts of said casing and conveyor forming a tumbling chamber, means supported by said casing between said heads for supplying a blast of abrasive to the inside of said chamber, means applying a suction to said first central opening, and means whereby spent abrasive is delivered out through said first central opening, said second central opening allowing air to flow into said chamber.

In testimony whereof I have hereunto set my hand.

LOUIS D. PEIK.
